The ornamental design for a pickup tool, as shown and described.

DESCRIPTION

FIG. 1 is a perspective view of a pickup tool in an open orientation, showing my new design;

FIG. 2 is a right side elevational view thereof;

FIG. 3 is a front or rear elevational view thereof;

FIG. 4 is a top plan view thereof;

FIG. 5 is a bottom plan view thereof; and

FIG. 6 is a front or rear elevational view of the pickup tool in a closed orientation;

FIG. 7 is a front or rear elevational view of the pickup tool of FIG. 1 having a bag inserted into a lower region of the pickup tool; and,

FIG. 8 is a front or rear elevational view of the pickup tool of FIG. 7 with the bag enveloping a lower region of the pickup tool.

The broken line showing the bag in FIGS. 7 and 8 is provided for the purpose of environment and forms no part of the claimed design.
